UNITED STATES PATENT OFFICE.

WILLIAM G. TEMPLETON, OF COLORADO SPRINGS, COLORADO.

VENDING-MACHINE.

1,385,933.

Specification of Letters Patent. Patented July 26, 1921.

Application filed September 30, 1919. Serial No. 327,414.

To all whom it may concern:

Be it known that I, WILLIAM G. TEMPLETON, a citizen of the United States, residing at Colorado Springs, in the county of El Paso and State of Colorado, have invented a new and useful Vending-Machine, of which the following is a specification.

This invention relates to vending machines and is designed more especially as an improvement upon the structure disclosed in Patent No. 1,293,979 issued to me on Feb. 11th, 1919.

One of the objects of the invention is to provide a machine capable of delivering stamps, checks, tickets, or the like in rows or transverse strips and to combine with the machine an indicator card or the like containing a novel arrangement of data whereby the user of the machine can, without hesitation, place the operating finger in correct position to dispense the number of stamps or other articles desired, whether said articles be requested by their value, the number of rows or the total number of articles.

Another object is to provide a combined weight and guide plate for use in connection with wide strips of stamps, tickets, or like articles, whereby the strips are held in proper position and will not buckle during the dispensing operation.

Another object is to provide a simple and efficient cutter movable transversely of the machine and which has means for yieldingly holding it in normal position.

A still further object is to provide simple and compact means for multiplying the speed of the cutter so as to insure a clean cut of the material being severed.

Another object is to combine a counter with the machine whereby the total number of stamps or other articles dispensed will be indicated, the means for actuating the counter being easy to operate and simple and accurate.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit of the invention.

In the accompanying drawings the preferred form of the invention has been shown. In said drawings—

Figure 1 is a plan view of the machine having the present improvements, parts being broken away.

Fig. 2 is a section on line 2—2, Fig. 1.

Fig. 3 is a section on line 3—3, Fig. 1.

Fig. 4 is a section on line 4—4, Fig. 3.

Referring to the figures by characters of reference, 1 designates a housing the rear portion of which forms a receptacle 2 adapted to hold the material to be dispensed. This material, which can be postage stamps, or the like, is preferably to be in a roll and the free end portion of the material is to be extended over a flat supporting strip or partition 3 extending from the compartment 2 to the front end of the housing and located below the top of the housing. Brackets 4 are secured to the sides of the housing at the front thereof and support a guide rod 5 on which a block 6 is mounted to slide. This block has a cutting wheel journaled therein, as shown at 7 and the shaft 8 of the wheel is provided with a gear 9 which is adapted to engage and to be rotated by a stationary rack 10 which is close to and parallel with the rod 5 and is attached at its ends to the sides of the housing. Both the guide rod and the rack are above the level of the supporting partition 3 and secured to the front of the housing slightly below the level of the partition 3 is a stationary shearing blade or strip 11 with which the wheel 7 cooperates.

Any suitable means may be provided for holding the wheel 7 normally at one side of the housing with the block 6 against one of the brackets 4. For example, a flexible member 12 may be connected to the block 6 and extended partly around a guide pulley 13 secured to one of the brackets 4, the said member then projecting backwardly along one side of the housing 1 and being connected to a spring 14 which is attached to the housing. Thus when the block 6 is moved along the rod 5 away from its normal position the spring will be placed under increased stress and the cutting wheel 7 will be rotated at a high speed relative to the blade or strip 11, due to the meshing of the gear 9 and rack 10, thus effectively cutting strip material fed across the path of the wheel. After the cutting operation has been completed the block 6 can be released.

and the spring will promptly return the parts to normal positions.

The sheet of material to be cut is adapted to be held flat upon the supporting partition 3 by a combined weight and guide plate 15 one end of which normally lies close to the path of the cutting wheel 7 while the other or back end of the plate is stiffened by a cross rod 16 the ends of which project beyond the sides of the plate and into slots 17 formed in the inner surfaces of the sides of the housing 1. Thus the plate is held against longitudinal displacement but can be readily swung upwardly or removed.

Longitudinal slots 18 extend into the plate from the front end thereof and the front end of the plate is provided, between the slots, with flat stiffening folds 19 constituting weights.

Mounted to slide on the housing 1 and bridging the space between the walls of the housing is a feeding member 20 to the bottom of which are connected devices, indicated at 21, for engaging and shifting the strip material when the member 20 is moved forwardly and for slipping over said material when the member 20 is moved rearwardly. These devices are of any desired construction but are preferably of the type disclosed in Fig. 2 and consist of a preferred number in Fig. 2 and consist of a preferred number of pivoted fingers having downwardly and forwardly inclined pointed terminals 22. This feeding means, in itself, constitutes no part of the present invention.

Formed along or secured to the feeding slide 20 is a longitudinal series of finger receiving members 23 which are consecutively numbered from "1" upwardly beginning with the rear member 23. These numbers indicate the number of strips of stamps or the like which will be dispensed from the machine when the feeding slide is actuated by placing a finger in the respective members 23. An index card 24 is arranged on the slide 20 in close proximity to the members 23 and is provided with columns of numbers parallel with and at opposite sides of the members 23. One column of numbers, indicated at 25 is provided at the rear end with the designation "Number of stamps" and if the strip material in the machine is made up of ten rows of stamps the first numeral in the column 25 will be "10" indicating that when one row of stamps is fed from the machine a total of ten stamps will be dispensed. The second numeral in the column 25 will be "20", the third "30" and so on in multiples of "10". These numerals register with the corresponding members 23 as shown. The other column of numbers indicated at 26 and located at the other side of the members 23 is provided for indicating the value of the strips or rows of stamps dispensed. For example if each stamp is valued at 2¢ the numeral "20"

will register with the member "1" and the numeral "10" in column 25, thereby indicating that one row of stamps, with ten in a row, is valued at 20¢. The second numeral in the row 26 will be "40", the third "60" 70 and so on so as to accurately indicate the value of the stamps dispensed whether in one, two or more rows. The column 26 is preferably provided at its back end with the designation "Value of stamps" and in 75 practice it is desired to have the numerals of column 26 in a color different from that of the numerals in column 25. Beyond the rear end of the series of members 23 may be arranged characters to indicate the value 80 of each stamp. For example, if the strip material is made up of two cent stamps the characters "2¢" can be placed at the place mentioned. It is to be understood that while the index described is for use in connection 85 with stamps, and more especially with two cent stamps, said index can be changed for use with stamps of other values, and for use with tickets, checks, and other articles in strip form.

A cover 27 is connected to the housing in any manner desired. In the present instance it is hinged thereto, as at 28 but it is to be understood that it can be connected in any other way preferred. The front end 95 of the cover overhangs the rear portion of the slide 20 and forms an abutment 29. In this abutment is journaled one end of a spiral 30 the other end of which is connected to a counter 31 carried by the cover 27 and adapted to be operated when the spiral is rotated in one direction. A slotted ear 32 is extended upwardly from the rear portion of the slide 20 and back of the abutment and the spiral 30 normally rests in the slot 100 in this ear. A weight 33 can be connected to the cover for holding it in closed position and for limiting the elevation thereof.

If a customer asks for stamps either by their number, their value or the number of rows, the user can instantly place a finger 110 in proper position for dispensing the number of stamps desired. For example if a customer should ask for twenty stamps the finger of the user would be placed in the 115 member 23 registering with the number 20 in column 25. The plate or slide 20 would then be moved rearwardly by means of this finger until the finger contacts with the abutment 29. This movement would cause 120 the terminals 22 of fingers 21 to slide backwardly over the stamps a predetermined distance. It would also cause the ear 32 to slide along the spiral and rotate it without operating the counter. The slide 20 125 would then be moved forwardly to its initial position and during this operation the fingers 21 would engage the strip material and slide it between the partition 3 and the guide plate 15, causing two strips or rows 130

of stamps to project forwardly beyond the cutting strip 11. At the same time the rotation of the spiral 30 by the ear 32 would be reversed and the counter would register 5 twenty stamps. On the completion of the feeding operation described the slide 6 should be moved transversely of the machine, as heretofore described so that the strip material would be severed and the 10 two projected rows of stamps delivered to the customer. The finger of the operator would have been as easily located in the same position at the beginning of the operation had the customer called for 40¢ worth 15 of stamps or for two rows of stamps.

When the machine is employed for dispensing stamps in rows of ten each the counter can be provided with a stationary cipher as shown at 34 so that the counting 20 will be by tens.

It is to be understood that the machine can be constructed for use in connection with strip material made up of less or more than ten rows and, while it is especially 25 useful for dispensing stamps, it is equally advantageous for dispensing tickets and other articles in strip form.

What is claimed is:—

1. A vending machine including means 30 for supporting strip material, a movable element thereabove having finger receiving members, means coöoperating with a finger inserted into a member for limiting the movement of said element in one direction, 35 means carried by said element for moving the strip material in the opposite direction, and separate means at opposite sides of each finger receiving member adapted to be indicated by the inserted finger for designating the number and value respectively 40 of articles vended by the placing of a finger in said member.

2. A vending machine including means 45 for supporting strip material, a feeding element mounted for reciprocation, separate finger receiving members movable therewith, means in the path of a finger engaging any one of said members for limiting the movement of the feeding element, 50 means along one side of said members for indicating the number of articles vended by the positioning of a finger in the respective members, and means along the other side of said members adapted to be indicated by 55 the finger engaging a receiving member, for designating the total value of the vended articles.

3. In a vending machine the combination 60 with a feeding element, an abutment, and finger receiving members movable with the element and relative to the abutment, said members being numbered to indicate the number of units of material vended by actuation of the feeding element by the placing 65 of a finger in the respective members, of

means along the sides of said members and movable therewith adapted to be indicated by the operating finger for designating the number of parts in the vended unit or units and the value of said units, respectively. 70

4. In a vending machine the combination with a housing and means therein for supporting strip material, of a combined weight and guide plate adapted to rest upon said strip material, said plate having transverse stiffening means at each end, there being a longitudinal slot in the plate intersecting the stiffening means at one end, co-operating means upon the plate and housing for holding the plate against longitudinal displacement, a slidable feeding element upon the housing and above the plate, and means carried by said element and movable in the slot for engaging and moving the strip material relative to the plate. 75 80 85

5. In a vending machine the combination with means for supporting strip material, and means mounted for back and forth movement for feeding the strip material from the machine in measured lengths, of 90 a stationary cutting strip below the path of the vended material, a cutting wheel movable along said strip and transversely of the vended strip to sever the strip material, and means for automatically returning the wheel to normal position when released. 95

6. In a vending machine the combination with means for supporting strip material, and means mounted for back and forth movement for feeding the strip material from the machine in measured lengths, of 100 a stationary cutting strip extending transversely of the vended material, a cutting wheel movable along said strip to sever the strip material, coöperating stationary and movable means for multiplying the rotation of the wheel during such movement. 105

7. In a vending machine the combination with means for supporting strip material, 110 and means mounted for back and forth movement for feeding the strip material from the machine in measured lengths, of a stationary cutting strip extending transversely of the vended material, a cutting wheel movable along said strip to sever the strip material, and coöperating stationary and movable means for multiplying the rotation of the wheel during such movement, 115 said means including a rack and a gear revoluble with the wheel and adapted to roll upon the rack. 120

In testimony that I claim the foregoing as my own, I have hereto affixed my signature in the presence of two witnesses.

WILLIAM G. TEMPLETON.
